UNITED STATES PATENT OFFICE.

THEODORE M. PRUDDEN, OF GRAFTON, MASSACHUSETTS.

BALL-BEARING-SPINDLE CONSTRUCTION.

Application filed January 19, 1923. Serial No. 613,731.

This invention relates to improvements in ball bearing spindles and the principal object thereof is to provide a novel self-aligning ball bearing spindle.

5 It is well known that in the operation of spindles when provided with a bobbin the geometrical axis of the spindle seldom passes through the center of gravity of the means comprising the spindle and the bobbin 10 mounted thereon. Consequently the support for the spindle must be so arranged as to provide for an oscillatory or gyratory movement of the lower end of the spindle in order that the spindle may so center itself as to 15 rotate about an axis passing through the center of gravity; otherwise it will be quite impossible to obtain a smooth and quiet running spindle at the high speeds which are employed in spinning.

20 Various means have heretofore been employed to permit the self-centering of the spindle. Such means usually have comprised a bolster located within the bolster case in which the spindle is mounted and 25 surrounding the lower end of the spindle, resilient means, such as, springs or fabric being employed to permit such oscillation of the bolster as is necessary to accommodate the gyratory motion of the spindle, but also 30 to check the secondary vibration and steady the self-centering movements of the blade.

In such constructions, and particularly where springs are employed to cushion the lower end of the spindle blade, the spring 35 tends to hold the blade in a particular position even though the spindle would naturally run in a slightly different position.

One of the objects of the present invention is to provide a bolster construction comprising a reservoir for a liquid having means 40 within the liquid acting upon the lower portion of the spindle blade to multiply the cushioning effect of the liquid upon the oscillatory or gyratory motion of the spindle.

45 More specifically the invention comprises one or more bolsters located in the reservoir of the bolster case and fulcrumed in the normal line of the axis of the spindle having means engaging the lower portion of the 50 spindle and operating as a lever or lever system to increase the cushioning effect of the liquid upon the oscillatory or gyratory movement of the spindle.

Another object of the invention is to provide 55 a ball bearing spindle with a novel form

of ball bearing which can be accurately made and readily assembled.

A further object of the invention is to provide a spindle blade with a ball bearing construction which forms with the blade a 60 unitary structure which, when assembled, cannot be tampered with.

A further object of the invention is to provide a spindle blade with a ball bearing assembled upon it and removable from the 65 bolster case with the blade.

A further object of the invention is to provide a ball bearing spindle with an upper ball bearing so mounted in the bolster case as to permit the axis of the ball bearing substantially to align itself with the axis of 70 the running spindle.

Another object of the invention is to provide a ball bearing placed approximately in line with the band pull to eliminate friction, 75 said spindle being mounted at its lower end to rotate with sliding friction instead of on ball bearings since it has been found that such small ball bearings as are required in the limited space will not withstand the 80 shocks of slamming bobbins on the spindles.

Other objects and features of the invention will more fully appear from the following description and the accompanying drawings and will be pointed out in the claims. 85

Preferred embodiments of the invention are illustrated in the accompanying drawings, in which,

Fig. 1 is a vertical axial sectional view through a spindle construction embodying 90 my invention, the spindle bolster, however, being shown in elevation;

Fig. 2 is an enlarged detail view in vertical section of the lower portion of the bolster case and telescopically arranged bolsters fulcrumed therein operable to cushion the oscillatory or gyratory movement of the lower end of the spindle blade, the lower end of the blade being shown in elevation;

Fig. 3 is a similar view showing a single 100 bolster within the bolster case, the lower end of the blade being shown in elevation.

The embodiment of the invention disclosed in Fig. 1 comprises a bolster case 1 having a base 2 adapted to rest upon the rail of the 105 spinning machine and provided with a screw threaded portion 3 to receive a clamping nut for securing the bolster case to the rail. The bolster case also is provided with a usual bracket and doffer guard which, being read-

ily understood by those skilled in the art, need not be described.

The bolster case is provided with a longitudinally extending cylindrical bore or chamber 4 to receive the lower end of the spindle to form a liquid-containing chamber or reservoir and means are provided within the liquid in said reservoir to multiply the cushioning effect upon the oscillatory or gyratory motion of the spindle when the latter is in an unbalanced state.

The preferred means for accomplishing this purpose comprises a bolster which is fulcrumed in the lower part of the bolster case and engages the spindle and acts as a lever to multiply the cushioning effect of the liquid upon the oscillatory or gyratory motion of the spindle blade.

In the particular construction illustrated in Fig. 1 the lower end of the bolster case is provided with a conical wall 5 having an apex 6 in line with the normal axis of the spindle blade 7. A bolster 8, having a downwardly tapered recess 9, encloses the lower end of the spindle blade, the taper in such recess being such as to permit the bolster to oscillate about its fulcrum and to act as a lever.

In the construction shown in Fig. 1 the lower end of the bolster 8 is provided with a conically tapered end wall 10 the apex of which engages and fulcrums upon the conical apex 6 of the wall 5 of the bolster case. The taper 10 is of steeper pitch than the taper of the conical wall 5 of the bolster chamber or reservoir. Consequently, the bolster is free to swing about its fulcrum in response to the oscillatory or gyratory movement of the lower end of the spindle.

In Fig. 2 a plurality of telescopically arranged bolsters are shown, the outer bolster 11 having a conically tapered bottom 12, the apex of which is fulcrumed upon the apex 6 of the conical bottom of the chamber 4 in the bolster. The outer wall 13 of this outer bolster desirably tapers inwardly toward the top and the inner wall 14 thereof preferably tapers outwardly from the bottom toward the top. The lower end of the outer bolster is provided with a conically tapering wall 15 the apex 16 of which serves as a fulcrum for the lower end of a similar inner bolster 17 the lower end of which is provided with a conical wall 18 the apex of which fulcrums upon the apex 16 of the conical wall 15. The conical wall 18 of the inner bolster has a steeper pitch than the conical inner wall 15 of the outer bolster so that the inner bolster is capable of rocking within the outer bolster. The inner wall 19 of the inner bolster, like that of the outer bolster, tapers outwardly from the bottom toward the top, thus providing a sufficient clearance to enable the inner and outer bolsters each to oscillate about its fulcrum in

response to the oscillatory or gyratory movement of the lower end of the spindle blade. The inner bolster, like the outer bolster, is provided with a conical face 20 which provides a step for the lower end of the spindle blade 7, the spindle blade having a conical end 21 of steeper pitch than the bottom 20 of the inner bolster.

In the construction illustrated in Fig. 2 the apexes of the conical ends 21 of the spindle 18 of the inner bolster and 12 of the outer bolster are in the normal axial line of the spindle 7. The respective bolsters, therefore, stand normally in axial alinement when the spindle is perfectly balanced, but upon vibration, oscillation or gyration of the lower end of the spindle the respective bolsters and spindle blade are able to oscillate about their respective fulcrums. As the upper ends of the bolster or bolsters may swing through a considerable arc the oil in the reservoir acts through the bolster or bolsters as through a lever or levers to cushion the oscillatory or gyratory motion of the lower end of the spindle.

By reason of the fact that these bolsters are of cylindrical or conical form their action is uniform throughout their entire periphery or peripheries so that a uniform cushioning or dampening effect upon the oscillatory or gyratory motion of the spindle blade is produced.

Any suitable upper bearing may be provided for the spindle blade. As illustrated herein a ball bearing of special construction is provided. In the preferred construction the spindle is provided with an inner ball race member 30 which is fixedly secured upon or formed as a part of the spindle and is provided with an under-cut race 31 for a series of balls 32. The complementary ball bearing member comprises an outer race member 33 which extends beneath the upper ball race member 30 and is provided with a cylindrical depending portion or downward extension 34 which telescopically fits in the upper end of the bolster case and preferably is slightly loose therein to permit the outer ball race to adjust itself automatically, axially in coincidence with the position assumed by the axis of the spindle by its self-centering action. The outer ball race is provided with a cap 35 having an inwardly extending wall or flange 36 which overlies the inner ball race member and serves to retain the race members and ball in their normal relative positions and also provides a unitary ball bearing construction which may be removed from the bolster case with the spindle.

Any suitable means may be provided for securing the cap to the lower ball race. As illustrated herein the lower edge portion of the cap 35 is provided with an inner annular recess which thins the wall of the cap and

provides the shoulder 37 adapted to rest upon the upper end of the ball race member 33. The thin portion 38, which extends downwardly from the periphery 5 of the end portion of the ball race may then be spun down upon the periphery of the outer ball race to make a permanent union so that tampering with the ball race, or 10 improper adjustments thereof by unskilled workmen are prevented.

In usual ball race constructions difficulty has been encountered in grinding the outer ball race accurately in commercial quantities. It is necessary to grind all ball 15 races internally to ensure their concentricity to within .0001". In the present construction this can be readily accomplished by properly chucking the depending portion or extension of the ball race in a suitable machine in which the race can be accurately 20 and rapidly ground and the cap can be applied and secured with equal facility in a suitable metal spinning machine.

The spindle is provided with a usual 25 whorl 39 having a V-shaped groove for the band and in this construction the plane of the apex of the band groove 40 desirably is slightly lower than the plane of the outer ball race so that the band normally tends to 30 draw the spindle down and retain it properly seated in its step in the bolster.

The spindle construction thus described permits an accurate self-centering of an unbalanced spindle with a minimum amount 35 of friction or resistance to the high speed of rotation of the spindle. In some ball bearing spindle constructions it has been thought necessary to fill the bolster chamber substantially full of oil, so that the ball 40 bearing is submerged in oil, but in such constructions an excess of oil is often delivered to the ball race and drips down upon the machine and the excess of oil is a detriment to the free rotation of the balls. In the 45 present construction the bolster case cannot be completely filled with oil and the lubrication of the ball bearing provided by the normal centrifugal action of the spindle carrying the oil from the reservoir to the 50 bearing without effecting any discharge of excess oil.

It will be understood that the embodiments of the invention disclosed herein are illustrative and not restrictive, and that various 55 changes in form, construction and arrangement of parts may be made within the spirit and scope of the following claims.

Having thus described my invention, what I claim as new, and desire to secure by Letters Patent, is:

1. A ball bearing spindle construction comprising a bolster case providing a reservoir for a liquid, a spindle blade rotatably mounted in ball bearings at the upper end 65 of said bolster case to resist downward thrust

of the spindle and an oscillatory hollow bolster pivotally mounted at its lower end in the lower portion of the bolster case in normal axial alignment with the spindle and freely movable at its upper end and having 70 in the lower end of the hollow recess an axial fulcrum for the lower end of said spindle and loosely enclosing a substantial portion of the lower end of said spindle, acting as a lever to multiply the cushioning effect of 75 the liquid upon the oscillatory or gyratory motions of the spindle.

2. A ball bearing spindle construction comprising a bolster case providing a reservoir 80 for a liquid, a spindle blade rotatably mounted in ball bearings at the upper end of said bolster case to resist downward thrust of the spindle and an oscillatory hollow bolster pivotally mounted in the lower portion of the bolster case having its fulcrum in 85 the normal line of the axis of the spindle blade and freely movable at its upper end in any direction and provided with a downwardly tapering recess loosely to receive the lower end of the spindle blade and having 90 an axial pivot for the lower end of the spindle with surrounding tapering walls extending upwardly to enclose a substantial portion of the lower end of the spindle and acting as a lever to multiply the cushioning 95 effect of the liquid upon the oscillatory or gyratory motions of the spindle.

3. A ball bearing spindle construction comprising a bolster case providing a reservoir 100 for a liquid, a spindle blade rotatably mounted in ball bearings in the upper portion of said bolster case to resist downward thrust of the spindle, an oscillatory outer bolster fulcrumed upon the base of said reservoir in the normal axial line of said spindle and having a downwardly tapering recess, an inner oscillatory bolster extending into the tapered recess of the outer bolster and also having a fulcrum in the normal axial line 105 of said spindle and provided with a tapered recess to provide a pivot for the lower end of said spindle blade, whereby said bolsters will act conjointly as a leverage system to multiply the cushioning effect of the oscillatory or gyratory motions of the spindle. 110

4. A ball bearing spindle construction comprising a bolster case providing a reservoir for a liquid, a spindle blade rotatably mounted in ball bearings in said bolster case acting to resist downward thrust of said spindle, a hollow oscillatory outer bolster having upwardly extending and upwardly tapering walls and a conical base, an inner oscillatory bolster having upwardly extending and upwardly tapering walls extending into the tapered recess of the outer bolster and having a fulcrum in the normal axial line of the spindle and provided with a tapered recess to provide a fulcrum for the foot of said blade in the normal axial line of the spindle, 130

whereby said bolsters will act conjointly as a leverage system to multiply the cushioning effect of the liquid upon the oscillatory or gyratory motions of the spindle.

5. A ball bearing spindle construction comprising a bolster case having a liquid containing chamber, a spindle blade provided with an inner ball race member, an outer ball race member removably mounted in the upper end of the bolster case and co-operating with the inner race member to resist lateral and downward forces acting upon the spindle and means in the lower portion of the bolster case pivotally mounted in axial alignment with the spindle and freely rotatable enclosing a substantial portion of the lower end of the spindle acting to multiply the cushioning effect of the liquid upon the oscillatory or gyratory motions of the spindle.

6. A ball bearing spindle construction comprising a bolster case, a spindle blade provided with an inner ball race member, an outer ball race member removably mounted in the upper end of the bolster case and co-operating with the inner race member to resist lateral and downward forces acting upon the spindle and a cover permanently attached to said outer race member and overlying the inner race member retaining the parts of the bearing in their relative positions and operable to permit removal of the spindle and race members as a unitary construction.

35 7. A ball bearing spindle construction comprising a bolster case providing a reservoir for a liquid, a spindle blade provided with

an inner ball race member, a co-operating outer ball race member having a depending portion mounted in the bolster case with sufficient clearance to permit said outer ball race to rock with the spindle and acting upon the spindle to resist downward thrust of the spindle and an oscillatory bolster fulcrumed in the lower portion of the bolster case in axial alinement with the spindle and freely movable at its upper end in any direction and provided with a fulcrum engaging the end of the spindle and having a tapering wall extending upwardly to enclose a substantial portion of the lower end of said spindle, whereby the bolster will act as a lever to multiply the cushioning effect of the liquid upon the oscillatory or gyratory motions of the spindle.

8. A ball bearing spindle construction comprising a bolster case providing a reservoir for a liquid, a spindle blade provided with an inner ball race member, a co-operating outer ball race member having a depending portion mounted in the bolster case with sufficient clearance to permit said outer ball race to rock with the spindle and acting upon the spindle to resist downward thrust of the spindle and a whorl on said spindle blade having a V-shaped groove for the driving band with the plane of the apex of said groove slightly lower than the plane of the outer ball race, whereby the band normally tends to draw the spindle down.

In testimony whereof, I have signed my name to this specification.

THEODORE M. PRUDDEN.
